LOCOMOTIVE SUPERHEATER

Virginius Z. Caracristi, Bronxville, N. Y., assignor
to The Superheater Company, New York,
N. Y.

Application November 3, 1936, Serial No. 108,944

7 Claims. (Cl. 122—481)

The present invention relates to superheaters, and particularly to an improved superheater construction adapted to be mounted in the combustion chamber of a locomotive boiler. This application is a continuation in part of my co-pending application, Serial No. 37,275, filed August 12, 1935.

A feature of the present invention is that the heat absorbing elements of the superheater extend transversely of a locomotive combustion chamber and are connected to inlet and outlet headers which are located exteriorly of water circulating tubes that line the side walls of the combustion chamber.

A second feature of the superheater construction disclosed herein is that any of its tubes may readily be cleaned without dismounting it from the locomotive.

Other features and advantages of the invention will become apparent upon consideration of the following detailed description and appended claims when read in conjunction with the accompanying drawings in which:

Fig. 1 is a longitudinal sectional view of a locomotive boiler showing the superheater of the present invention applied thereto;

Fig. 2 is a horizontal sectional view on the line 2—2 in Fig. 1;

Fig. 3 is a transverse sectional view on the line 3—3 in Fig. 1;

Fig. 4 is a top plan view on an enlarged scale and shows the construction of the superheater units;

Fig. 5 is an enlarged side elevational view showing the manner in which the superheater units are arranged with respect to each other;

Fig. 6 is an enlarged scale view, partly broken away, and shows the construction of a section of a superheater unit at each end thereof, the view being along the line 6—6 in Fig. 4;

Fig. 7 is a sectional view on the line 7—7 in Fig. 6; and

Fig. 8 is a sectional view on the line 8—8 in Fig. 6.

Referring to the drawings, the numeral 10 designates a steam and water drum disposed centrally above the fire box 12 and the adjacent combustion chamber 13 of the locomotive. Drum 10 extends partly over a water barrel 14 and communicates with the upper central portion of the latter through several large nipples 15, one of which is shown in Fig. 1. The water barrel 14 is provided in usual manner with fire tubes and flues connected between the back sheet 16 and a front sheet which is not shown. Other large nip-

ples 18 connect the lower side portions of barrel 14 to a pair of water drums 20 disposed along and outwardly of the lower sides of combustion chamber 13 and fire box 12.

The side walls of the fire box and combustion chamber are lined with closely spaced water circulating tubes 21 connected at their lower ends into the drums 20 and at their upper ends into individual headers 22 (Fig. 3) which in turn are connected to the steam and water drum 10 by tubes 23 extending partially across the top of the fire box and combustion chamber. The use of individual headers provides for unequal expansion or contraction of these tubes due to varying temperatures along the fire box and combustion chamber and also facilitates cleaning of these tubes.

A series of small pipes 42, having their upper sides within the drum 10 cut away, conducts steam to dry pipes 43 which supply the inlet headers for superheater units located in combustion chamber 13. The headers 44 are disposed vertically outside the wall tubes 21 at each side of the combustion chamber and the heat absorbing portions of the superheater units 46 extend transversely of the combustion chamber, projecting from the latter at their ends between more widely spaced wall tubes 21. The units that connect the inlet header 44 at either side of the boiler to the outlet header 47 at the same side thereof are nested or intercalated longitudinally of the chamber 13 with those connected to the headers at the other side of the chamber, as shown in Figs. 2 and 4. The superheater outlet headers are also disposed vertically outside the wall tubes 21 and are connected to conduits 48a extending forwardly along the sides of the locomotive to the throttle (not shown).

The superheater 45 is protected by a screen comprising staggered riser tubes 51 connecting at their lower ends into a transverse header 52 communicating with drums 20 and also connected radially into drum 10 at their upper ends. A dry pipe 53 receiving steam from drum 10 through pipes 54, similar to pipes 42, supplies saturated steam to superheater elements 55 disposed within the flues of barrel 14, the superheated steam from these units mixing with that from the units in the combustion chamber.

The superheater arrangement described above is as disclosed in my aforesaid application. An improved form of construction for the units of the superheater is illustrated in Figs. 4 to 8. A plurality of superimposed units connect an inlet header 44 at one side of the superheater to the

outlet header 47 at the same side thereof and extend in loop form back and forth across the combustion chamber. As mentioned above, units 48 connected to headers at one side are intercalated between the looped portions of units 49 connected at their ends to the headers at the other side of the combustion chamber. Each of the units 48, 49 is divided into a plurality of sections 50, 51 connected for continuous steam flow by auxiliary headers or coupling members 52, 53. Each section, as 50, comprises two spaced pairs of parallelly extending tubes, the tubes 54 and 55 of one pair being vertically aligned and comprising an inlet section. The tubes 58 and 60 of the other pair are similarly aligned and comprise an outlet section. At one end the tubes of each pair are joined by an integrally formed breeches piece 62, 64 to each other and to a single tube length 66, 68 projecting between the circulating tubes 21 and received at its outer end in the hollow coupling member 52 which provide for continuous steam flow through contiguous sections of a unit. The inlet branch 54, 56 of the first section of a unit and the outlet branch 58, 60 of its last section communicates respectively with the inlet and outlet headers 44 and 47 respectively. The coupling member 52 is formed with clean-out openings normally closed by plugs 70 and the axes of these openings are so disposed with respect to those of the tubes, such as 54, 56 that a clean-out tool may be inserted into either by way of the single tube length 66, or the tube length 68 for the tubes 58, 60. At their other ends one tube, as 54, of each pair is adjoined to the nearest adjacent tube, as 58, of the other pair by an integrally formed breeches piece 72, 74 at the inner end of single tube lengths 76, 78 which in turn are joined by a breeches piece 80 terminating in a single tube length 82 received in a drain box 84, or 85 for the units 49. The drain boxes 84, 85 are located outside the rows of circulating tubes 21 and the single tube lengths 76, 78 connecting with the breeches pieces 72, 74 joining the tubes 54, 58 and 56, 60 respectively, with the breeches piece extend between the circulating tubes 21 so that the breeches piece 80 joining these single tube lengths 76, 78 at their outer ends does not obstruct gas flow.

Inasmuch as the units connected between the inlet and outlet headers at one side of the superheater are intercalated with those connecting with the headers at the other side, the drain boxes 85 for the units 49 are located at the same side of the superheater as the coupling members 52 for the other set of units 48, and vice-versa. The two pairs of tubes forming a section of a unit are staggered with respect to each other. The coupling member joining one section of any unit to its next contiguous section extends beneath the drain boxes for the sections of units communicating with the headers on the other side of the superheater, each coupling member receiving the single tube length 68 of the outlet branch 58, 60 of each section is turned upwardly at its forward end to meet the single tube length 66 leading to the inlet branch 54, 56 of the following section. Thus, the coupling members for one set of units are nested with the drain boxes for the other set of units. Accordingly mutual support of the units is obtained from top to bottom and the lowermost units may be supported upon the water drums 20 of the boiler.

It may be seen that the superheater construction described above is so compact that a considerable amount of superheating surface may be lo-

cated within the combustion chamber of a locomotive boiler. At the same time any of the tubes comprising the superheater may be individually cleaned because convenient access is afforded thereto through the related clean-out openings 5 in the coupling members 52, 53 and all of the latter may be reached by removing the outer casing plates 90, Fig. 2. Furthermore, whenever any tube requires repair or replacement it is not necessary to remove the entire unit but only the 10 section of which the particular tube forms a part, the section being withdrawn between tubes 21 after disconnecting it from the coupling members joining it to the preceding and following sections 15 of the unit.

What I claim is:

1. In a superheater; inlet and outlet headers; a heat absorbing unit connected between said headers and divided into a plurality of sections each having a steam inlet branch and a steam outlet branch parallel thereto, each branch comprising a pair of parallel tubes connected at each end by a breeches piece to the inner ends of single tube lengths; coupling members receiving the outer ends of the single tube lengths at one end 25 of each branch and connecting the section to the preceding and following sections of the unit for circulation of fluid in series therethrough; and breeches pieces joining the outer ends of the single tube lengths at the other end of both 30 branches to another single tube length; and means closing the outer end of said mentioned single tube length.

2. In a superheater; inlet and outlet headers; a heat absorbing unit connected between said 35 headers and divided into a plurality of sections each having a steam inlet branch and a steam outlet branch parallel thereto, each branch comprising a pair of parallel tubes connected at each end by a breeches piece to the inner ends of single 40 tube lengths; coupling members receiving the outer ends of the single tube lengths at one end of each branch and connecting the section to the preceding and following sections of the unit for circulation of fluid in series therethrough; and breeches pieces joining the outer ends of the single tube lengths at the other end of both 45 branches to another single tube length; and a drain box receiving the outer ends of said last mentioned single tube length and formed with a 50 normally closed opening for discharging fluid from any of the tubes constituting said inlet and outlet branches of a section of a unit.

3. In a boiler having a combustion chamber, and rows of spaced fluid circulating tubes arranged on opposite walls of said chamber; a superheater having inlet and outlet headers located exteriorly of said tube rows and heat absorbing units disposed within and extending across said chamber, each unit being divided into 60 a plurality of sections having inlet and outlet branches each comprising a pair of parallel tubes connected at each end by breeches pieces to the inner ends of single tube lengths projecting between said circulating tubes; coupling members 65 located exteriorly of said circulating tubes at one side of said chamber and receiving the outer ends of the single tube lengths at one end of each branch of a section and connecting said section to the preceding and following sections of the 70 unit, the axes of said last mentioned single tube lengths being aligned with normally closed clean-out openings formed in the related coupling member and located with respect to the axes of the pair of tubes joined thereto so that a cleaning 75

tool may be inserted into either of said pair of tubes; breeches pieces joining the outer ends of the single tube lengths at the other end of the component branches to another single tube length projecting between the row of circulating tubes at the opposite side of said chamber; and drain boxes located exteriorly of last mentioned tube row and receiving the outer ends of last mentioned single tube lengths, said boxes being provided with normally closed openings for discharging fluid from any of the tubes of each section of a unit.

4. A tubular heat absorbing element for a superheater or the like having inlet and outlet branches each comprising a pair of parallel tubes joined at one end thereof by breeches pieces to single tube lengths adapted to connect with fluid circulating headers; breeches pieces joining the other ends of one tube of each branch to one tube of the other branch and to the inner ends of single tube lengths; and a breeches piece joining said last mentioned single tube lengths to each other and to another single tube length; and removable closure means closing the outer end of said single tube length.

5. In a locomotive boiler having a combustion chamber; rows of spaced fluid circulating tubes lining the side walls of said chamber; a superheater having an inlet header and an outlet header located exteriorly of the rows of tubes at one side of said chamber; a heat absorbing element connected between said inlet and outlet header divided into a plurality of sections each comprising two pairs of parallelly extending tubes; breeches pieces joining the tubes of each pair at one end to each other and to single tube lengths projecting between the tubes of the row at one side of said chamber; a coupling member positioned exteriorly of said tube row and connecting the single tube length leading from one pair to the preceding section of the unit and that from the other pair to the following section; breeches pieces joining the other end of one tube of each pair to the adjacent tube of the other

pair and to single tube lengths projecting between the tubes of the row at the opposite side of said chamber; a breeches piece joining said last mentioned single tube lengths to each other and to another single tube length; and removable closure means closing the outer end of last mentioned tube length.

6. In a superheater having a plurality of units each divided into a plurality of coupled sections as recited in claim 2; inlet headers at opposite sides of the superheater each spaced from an outlet header at the same side of the superheater, the said sections which constitute a unit that connects with the inlet and outlet headers at one side of the superheater being intercalated longitudinally of the superheater with the sections that constitute a unit connected with the inlet and outlet header at the opposite side of the superheater and the coupling members joining the contiguous sections of each unit each extending beneath and supporting a drain box for a section of a unit connected between the headers at the other side of the superheater.

7. In a superheater; an inlet header and outlet header at each side thereof; a plurality of sectional heat absorbing units, as recited in claim 2, connected between each inlet and outlet header and arranged in parallel rows with units which are connected to the inlet and outlet header at one side of said superheater intercalated longitudinally of the latter with the units that are connected to the headers on the other side of the superheater, the coupling members joining contiguous sections of the respective units being arranged in spaced horizontal rows at the same side of the superheater as the headers to which the respective units are connected and the related drain boxes being arranged in spaced horizontal rows at the opposite side of the superheater and located between and supported by coupling members that join the sections of units connecting with the headers at said opposite side; and means supporting the lowermost units.

VIRGINIUS Z. CARACRISTI.
